Lida M. Webb.

UNITED STATES PATENT OFFICE.

LIDA M. WEBB, OF GALENA, ILLINOIS.

DESIGN FOR A SPOON.

SPECIFICATION forming part of Design No. 21,193, dated December 1, 1891.

Application filed October 8, 1891. Serial No. 408,171. Term of patent 3½ years.

To all whom it may concern:

Be it known that I, LIDA M. WEBB, a citizen of the United States, residing at Galena, in the county of Jo Daviess and State of Illinois, have invented and produced a new and original Design for Spoons, of which the following is a specification, reference being had to the accompanying drawing, forming part thereof.

10 The drawing is a detailed front view of my newly-designed spoon, it being deemed unnecessary to more fully illustrate my design.

I am aware that heretofore spoons have been made which presented when viewed in front, 15 as in the drawing, handles of both plain and ornamental designs.

The leading feature of my design consists in a spoon having an ornamental handle, as

shown in the drawing, upon which are pressed out in bas-relief an army hat and sword on either side. The sword extends along the narrow part of the handle about two-thirds its length. The hat occupies the extreme end of the handle at its widest part. The hat and sword are so placed as to convey the idea that they are linked together, thus presenting to the eye the effect that they were laid or put thereon.

I claim—

The design for a spoon herein shown and described.

LIDA M. WEBB.
